CLAIM

The ornamental design for a grille insert for displaying logo design (Ford design), substantially as shown and described.

DESCRIPTION

FIG. 1 is a front elevational view of a grille insert for displaying logo design (Ford design) showing my new design.

FIG. 2 is a bottom plan view thereof, the top plan view being the same; and,

FIG. 3 is an end elevational view thereof as taken from the left of FIG. 1, the opposite end view being the same.
